HOSPITAL DOOR LATCH MECHANISM

Henry G. Voight, Hamden, Conn., assignor to
Sargent & Company, New Haven, Conn., a cor-
poration of Connecticut

Application December 4, 1943, Serial No. 512,849

2 Claims. (Cl. 292—173)

This invention relates to door latches, and more particularly to a door latch adapted for use on hospital doors, or in locations where a person desiring to open the door may not have his hands free to operate the latch.

It is desirable to provide some form of latching device for doors in hospitals and like institutions to hold them in closed position. On the other hand, nurses and attendants often carry articles in their hands, and thus do not have their hands free to operate a knob or other door handle of usual character. It is, therefore, advantageous to provide a handle or other operating member on the face of the door of such construction that it may be operated by pressure of the arm or wrist, so that anyone desiring to open the door may operate the latch and pull the door to open position without necessarily using the hand or fingers for this purpose.

It is also advantageous to have similar operating members on both sides of the door, so that the door may be opened from either side and the operating members be made in duplicate to save manufacturing costs.

One object of the present invention is to provide a latch and latch-operating mechanism of novel construction for hospital doors or the like.

A further object of the invention is to provide a latch for hospital doors or the like, which latch is operated by a handle pivotally mounted upon the face of the door and designed to be moved about its pivot by pressure of the arm or wrist.

A still further object of the invention is to provide a latch structure of the character described wherein the handle mechanism will be duplicated upon opposite sides of the door, so that the bolt may be retracted from either side.

A still further object of the invention is to provide a door latch of the character described having a latch bolt operated by a handle pivoted intermediate its ends to the side of the door, one end of the handle being connected directly to the latch bolt to operate the same, while the end of the handle upon the other side of the pivot is spaced from the door so that anyone desiring to open the door may readily insert the wrist or arm between the face of the door and the free end of the handle.

To these and other ends the invention consists in the novel features and combinations of parts to be hereinafter described and claimed.

In the accompanying drawing:

Fig. 1 is an elevational view of the edge of a door having mounted thereon a latch and latch-operating members embodying my improvements;

Fig. 2 is an elevational view of the face of the door showing the latch mechanism;

Fig. 3 is a sectional view on line 3—3 of Fig. 2;

Fig. 4 is a sectional view on line 4—4 of Fig. 2; and

Fig. 5 is a view of the latch bolt and case, the cover of the case being removed to show the interior construction.

To illustrate a preferred embodiment of my invention, I have shown a portion of a door at 10, in the edge of which is a cylindrical opening or bore 11 in which is disposed a lock case 12, which case will be of generally cylindrical form but is flattened at its sides adjacent the rear thereof, as shown at 13. The case is provided with a face plate 14, which may be secured to the door by the screws 14^a, thus securing the case to the door.

The bolt mechanism may be of very simple form, such, for example, as shown in Fig. 5, in which is shown a bolt 15 adapted to project from the case and carried by a bolt stem 16 slidably mounted in the case. The bolt is urged to protruded position by a spring 17 acting against the bolt head at one end, and at the other end against a post 18 fixed to the case. Adjacent its rear end the bolt stem is provided with an opening 19 to receive latch-operating members, as will be presently described, and in registration with this opening the casing is provided with elongated openings 20 in each of the opposite side walls.

The latch construction above described is adapted to be operated by handles pivoted to the door, one at each side thereof. These handles are shown at 21, and are of a form designed to be used upon doors of public institutions such as hospitals. These handles are secured upon the face of the door and are provided with free ends 22 designed to be spaced from the door so that the arm or wrist of a person desiring to enter the room may be inserted between the handle and the door, or may engage the handle at one side thereof without interference from the door.

As shown, each of the handles is pivoted to the door adjacent its central portion, and for this purpose is provided with a post 23 having a reduced portion 24 rotatably mounted in a plate 25 secured to the door by fastening members such as screws 26. The post 23 may be secured to the plate 25 by means of a washer 27 on the inner side of the plate, which washer is secured to the post by a screw 28, thus pivoting the arm to the door to swing about a horizontal axis perpendicular to the face of the door. It will be understood that normally the plate 25 will be secured upon the post 23 before the former is secured to the door.

by the screws 26, and the connection of the door handle with the latch bolt mechanism is constructed to permit this method of assembling the parts, as will presently appear.

Each of the handles adjacent its upper end, as shown, and on the side of its pivot opposite the free end 22 is provided with a spindle 30 adapted to be inserted through elongated slot 31 formed in the door, which slot communicates with the bore 11 and also lies opposite the corresponding opening 20 in the lock case, so that the spindle 30 enters the lock case and extends into the opening 19 of the bolt stem 16. It may be noted that the openings 20, as well as the openings 31, are somewhat wider than the width of the spindles 30, so as to allow for the movement of the spindle in an arcuate path when the handle is turned about its pivot. This is also true of the opening 19 in the bolt stem.

It will be noted that the spindles 30, entering from either side of the door, each extend into the opening 19 of the bolt stem so that the bolt may be retracted by the pivotal movement of either handle.

In order to open the door it is only necessary to exert pressure of the arm or wrist, for example, on the free end 22 of the door handle in the direction to move this end of the handle toward the edge of the door. As the handle constitutes a lever of the first class, this will, as is obvious, move the upper end of the handle in a direction away from the edge of the door, and thus serve to retract the bolt 15 against the pressure of the spring 17, whereupon the door may be opened. Upon release of the handle the spring 17 will restore the parts to their former positions.

At their upper ends the door handles may be provided with face portions 33, which are horizontally elongated to conceal the openings 31, and it may also be noted that the plates 25 may be spaced slightly from the faces of the door by their laterally turned edges 34 so that the washer 27 will be free to rotate with the door handle and not bind between the plate and the door.

While I have shown and described a preferred embodiment of my invention, it will be understood that it is not to be limited to all of the details shown, but is capable of modification and variation within the spirit of the invention and within the scope of the claims.

What I claim is:

1. A latch for hospital doors or the like comprising a casing, a latch bolt reciprocably mounted therein, a handle pivoted at a point intermediate its length to the face of the door and arranged to swing about an axis perpendicular to said face, said handle having a body portion spaced from the door including a freely depending lower end extending below the pivot point and having an inwardly projecting part at its upward end extending toward the door, a spindle carried by said last-named part and projecting into an opening in the door and into the casing, and means connecting said spindle to the bolt to withdraw the same when the handle is swung about its pivot.

2. A latch for hospital doors or the like comprising a casing, a latch bolt reciprocably mounted therein, a handle having a body portion spaced from the door, a post secured to an intermediate part of, and projecting inwardly from, the body portion of the handle, said post being pivoted to the door whereby the handle may swing about an axis perpendicular to the face of the door, said handle having a part at the upper end of the body portion turned toward the door, a spindle carried by said part and projecting into an elongated opening in the door, said casing having an elongated opening to receive said spindle, means connecting the spindle to the latch bolt to withdraw the latter when the handle is swung about its pivot, and the body portion of said handle including a freely depending lower end spaced from the door and directed outwardly therefrom for manual engagement.

HENRY G. VOIGHT.
